(57) **CLAIM**

I claim the ornamental design for a water bottle lid, as shown and described.

DESCRIPTION

FIG. 1 is a perspective view of a water bottle lid showing my new design;

FIG. 2 is a side view thereof;

FIG. 3 is front view thereof;

FIG. 4 is a rear view thereof;

FIG. 5 is a bottom plan view thereof; and,

FIG. 6 is a top plan view thereof.

The broken lines in the figures are for illustrative purposes only and form no part of the claimed design.
